[57] CLAIM

I claim the ornamental design for a portable wire dispensing reel for barbed wire, as shown.

DESCRIPTION

FIG. 1 is a perspective view of a portable wire dispensing reel for barbed wire showing my new design;

FIG. 2 is a typical side elevational view thereof;

FIG. 3 is a top plan view thereof;

FIG. 4 is a front elevational view thereof; and,

FIG. 5 is a rear elevational view thereof.
